UNITED STATES PATENT OFFICE.

NELSON C. DURAND, OF NEWARK, NEW JERSEY, ASSIGNOR TO NEW JERSEY PATENT COMPANY, OF WEST ORANGE, NEW JERSEY, A CORPORATION OF NEW JERSEY.

PHONOGRAPH HEARING-TUBES.

1,096,024.

Specification of Letters Patent. Patented May 12, 1914.

Application filed March 1, 1910. Serial No. 546,675.

To all whom it may concern:

Be it known that I, NELSON C. DURAND, a citizen of the United States, and a resident of Newark, in the county of Essex and State 5 of New Jersey, have invented certain new and useful Improvements in Phonograph Hearing-Tubes, of which the following is a description.

My invention relates to hearing tubes for 10 phonographs, and the objects thereof are the provision of light, durable and rigid tubes which are connected to a flexible connecting tube in a simple and effective manner whereby the ear pieces of the tubes may 15 readily be adjusted and retained in position in the ears of the operator.

My invention is an improvement on the construction shown in application of Charles L. Hibbard, Serial No. 511,443, filed August 20 5, 1909, for phonograph hearing tubes. In the construction disclosed by the said Hibbard, rigid ear tubes are connected to the flexible tubing by means of a rigid Y connection, the arms of which are connected to 25 the metallic ear tubes by flexible connections, the position of the ear tubes being regulated by a friction device mounted between the same. In my construction, I provide a connection between the flexible tubing 30 and the ear tubes, which is in effect a Y connection, the arms of which are adjustable toward and from each other, and are held in adjusted position by friction. The ear tubes are connected directly with the 35 arms of the Y. By the construction indicated, I do away with the flexible tubing between the arms of the Y and the metallic ear tubes, and with the friction device mounted across the lower ends of the ear 40 tubes.

Other objects of my invention consist in the construction of parts and combinations of elements as hereinafter more particularly described and pointed out.

Reference is hereby made to the accompanying drawings forming part of this specification and representing a construction embodying my invention, in which—

Figure 1 represents a side elevation of a 50 pair of ear tubes and connected parts. Fig. 2 is a cross section on line 2—2 of Fig. 1, the holding screw being shown in side elevation.

Referring to the drawings, ear tubes 1, 2 are preferably of metal or other rigid con-

struction and are provided with ear tips 3, 55 3 of soft rubber or other suitable material which may be adjusted in the ears of the operator, and which may be renewed when necessary. The tube 1, at its lower end is secured within a short tubular portion 4 of 60 the hollow body or barrel 5 having an extension at right angles to the portion 4. The tube 2 is connected in like manner to the hollow barrel 6, which latter has a tube 7 integral therewith or secured thereto 65 opening into the interior of barrel 6 substantially in line with the opening of tube 2 thereinto. This tubular extension 7 is connected to the flexible tubing 8, the lower end of tube 7 being inserted within the upper 70 end of flexible tube 8 or otherwise connected thereto. Tube 8 leads to the phonograph reproducer.

The hollow members or barrels 5 and 6 are mounted with their open ends axially in 75 line with each other, and in such a manner as to be rotatable relatively to each other while forming a substantially air-tight joint. As illustrated in the drawings, I prefer to bevel the adjacent inner ends of barrels 5 and 6, as shown at 9, the barrels 5 and 6 being held in contact upon the beveled surface 9 by any suitable means as the screw 10 extending axially through barrels 5 and 6. A split washer or other suitable 80 friction means 11 may be interposed between the head of the bolt 10 and the outer surface of one of the barrels, as 5, to regulate the pressure exerted upon each other by barrels 5 and 6. As shown in the drawings, 85 the tips 3 of the ear tubes 1 and 2 are directed toward each other and are so arranged that a line joining the exit openings therein invariably lies in a plane substantially at right angles to the axis of the barrels 5 and 90 6 and the bolt 10. By this construction, the ear tubes 1 and 2 may be moved toward and from each other to obtain the proper adjustment of ear tips 3, into and out of the ears of the user, the ear tubes being held in adjusted position by the friction exerted by one barrel upon the other in the rotation of the same. It is obvious that if desired barrels 5 and 6 might telescope within each other or within a connecting intermediate tubular 100 member, or abut against each other at their inner surfaces without the formation of a bevel upon the same.

Having now described my invention, what I claim and desire to protect by Letters Patent is as follows:

1. In hearing tubes, the combination of a pair of hollow ear tubes, and a pivotal connection between said ear tubes, the interiors of said ear tubes communicating with each other through said pivotal connection, said ear tubes having their outer or exit portions directed toward each other and so arranged that a line joining the centers of the exit openings therein invariably lies in a plane substantially at right angles to the axis of said pivotal connection, substantially as described.
2. In a device of the class described, the combination of a plurality of hollow barrel-like members arranged in axial alinement with each other, each member having an open end engaging and communicating with an open end in the other, means connecting said members for relative rotation about their common axis, one of said members having a hollow inlet portion, and an ear-

tube extending from and communicating with each member, substantially as described.

3. In a device of the class described, the combination of a plurality of hollow barrel-like members arranged in axial alinement with each other, each member having an open end communicating with an open end in the other, and one of said members having a hollow inlet portion, means comprising a fastening member passing axially through said barrel-like members for connecting the latter for relative rotation about their common axis, and an ear-tube extending from and communicating with each barrel-like member, substantially as described.

This specification signed and witnessed this 28th day of February 1910.

NELSON C. DURAND.
